UNITED STATES PATENT OFFICE

NICHOLAS D. WALTER, OF PHILADELPHIA, PENNSYLVANIA

GARMENT

Application filed November 11, 1929. Serial No. 406,413.

This invention relates to an improved under garment, which may be a shirt, drawers or B. V. D.'s, and the purpose of the invention is to provide a garment comprising inner and outer sections, the inner section or layer being constructed of knitted pure cotton, the surface of which next to the skin to have a soft smooth facing, while the outer section or layer is constructed of thin knitted pure wool, the outer section or layer being one-half size larger than the inner section or layer, so as to allow for shrinkage.

This character of garment provides a protecting covering for the body in order to prevent the body from infection, and by the wearing of a garment of this kind it enables the body to have the proper ventilation, preventing the pores from clogging up, which would result in a tired, lazy feeling and a greatly lowered vitality. In other words a garment of this kind would allow the waste matter to evaporate through the pores of the skin and hence avoid a tired, lazy feeling.

It has been cited by the medical profession that woolen underwear next to the body is very undesirable, making the person too warm and uncomfortable, especially when changing temperatures. Experience has shown that heavy underwear is a frequent cause of illness. This is due to the fact that woolen material next to the skin causes perspiration and due to the underwear being heavy the impurities cannot evaporate quickly enough when the wearer goes out doors, thereby contracting illness.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:—

Figure 1 is a view of a garment in the form of a shirt, showing the same construction of inner and outer layers.

Figure 2 is a sectional view on line 2—2 of Figure 1.

Referring to the drawings, 1 identifies an undergarment, which is composed of inner and outer layers or sections, the outer layer being at least a one-half size larger than the inner layer, thereby allowing for shrinkage.

The inner layer is composed of pure knitted cotton, the face thereof next to the body has a soft smooth surface, which lies flat against the body, and thereby allows the impurities to evaporate and be carried off, when reaching the surface of the skin.

The outer section 2 is attached at intervals as identified at 3 to the inner layer 1a. In other words when constructing the garment, that is knitting both layers, both layers or sections are inter-knitted at intervals, so that the inner and outer layers will remain in conformity with each other.

The outer layer is constructed of thin knitted pure wool, which provides for heat to the body, yet it does not contact with the skin of the body, and therefore will not irritate the skin and make the body excessively warm.

By providing an under garment of this kind having the inner and outer layers, the garment is provided with an air chamber between the two layers, and due to the inner and outer layers being in motion with the movements of the body, setting up a proper "air flow", the skin is kept thoroughly ventilated and in a healthy condition. A garment of this kind absorbs the perspiration normally and naturally and allows the skin full activity which is so necessary to health. A garment of this kind also maintains a wholesome body temperature at all times, indoors and out. Furthermore a garment of this character is cleaner in that moisture evaporates against sudden temperature changes in heat or cold and at the same time prevents illness to a maximum degree.

From the foregoing it will be noted that the two fuzzy or knap surfaces of the two thicknesses or layers of the garment face together or toward each other, so as to provide for the air chamber and thereby create the proper air flow. The plain pure cotton sur-

face therefore contacts with the body and lies flat thereagainst, allowing the body to have free movement in the garment.

The inner thickness or layer of the under garment is made up of relatively open knitted work or mesh, in fact not too closely woven, though the tightness of the weave is to be governed by various developments and experiments. In other words it is the aim to provide the inner thickness or layer of the garment of such a knitted weave as to permit the moisture to evaporate freely through the inner layer or thickness, and to give off the impurities, such moisture as for instance perspiration will thereby be absorbed by the pure woolen outer thickness of the garment through capillary attraction.

It is obvious that the weave of the inner thickness or layer may be varied according to circumstances and according to various developments as may be derived from experiments. The whole matter of invention resides in making the inner thickness of the proper mesh as may be understood from this description, the outer woolen thickness or layer likewise woven, the two thicknesses having their knap or fuzzy surfaces facing each other, hence providing air chambers between the two thicknesses.

It is also to be understood that the lower edge of the body of the garment as well as the sleeves are open, that is at the edges of the lower part of the body of the garment as well as the lower edges of the sleeves are unattached, namely the lower edges of the inner and outer thicknesses are unattached, as identified at 3a.

The invention having been set forth, what is claimed is:

An undergarment comprising inner and outer thicknesses, the inner thickness being made of cotton, the outer thickness being made of wool, the inner adjacent faces of both thicknesses having a knap, said faces contacting with each other, thereby providing an air space between the two thicknesses to insure a proper air flow, said inner and outer thicknesses being interconnected or interknitted along vertical lines, said vertical lines being at spaced intervals, thereby maintaining uniformity between the two thicknesses of the garment, the lower edges of the inner and outer thicknesses between the lines of connection being free and unattached.

In testimony whereof he affixes his signature.

NICHOLAS D. WALTER.
